SPRING SCALE

Albert F. Bujan, Waukegan, Ill., assignor to Abbott Laboratories, North Chicago, Ill., a corporation of Illinois

Filed Mar. 29, 1962, Ser. No. 69,486

Term of patent 14 years

(Cl. D52—10)

FIGURE 1 is a front elevational view of a spring scale, showing my new design;

FIGURE 2 is a side elevational view of one side thereof;

FIGURE 3 is a rear elevational view thereof;

FIGURE 4 is a top plan view thereof; and

FIGURE 5 is a bottom plan view thereof.

The other side thereof is the same in appearance as the one side.

I claim:

The ornamental design for a spring scale, substantially as shown and described.
